UNITED STATES PATENT OFFICE.

MATHIAS L. JOLLY, OF NEW YORK, N. Y., ASSIGNOR TO CHRISTIAN C. BOHN, OF NEW YORK, N. Y.

ILLUMINATED SIGN OR PICTURE.

SPECIFICATION forming part of Letters Patent No. 729,598, dated June 2, 1903.

Application filed July 23, 1902, Serial No. 116,756. (No model.)

To all whom it may concern:

Be it known that I, MATHIAS L. JOLLY, a citizen of the United States, residing in New York, in the county of New York and State of New York, have invented certain new and useful Improvements in Illuminated Signs or Pictures, of which the following is a specification.

The present invention relates to pictures and signs for ornamenting and advertising purposes, and especially to that class of such apparatus which are rendered more brilliant and visible by the employment of sources of artificial light.

The object of the present invention is to cause the picture to itself emit light, as it were, and to provide means for readily changing the subject of the picture or sign in a simple and efficient way without material trouble and without changing the whole arrangement of the parts of the apparatus. This object and others which may more fully appear hereinafter are accomplished by placing the design to be exhibited upon a series of reflecting elements, each element carrying part of the design and a part of each element acting as a reflector to reflect light-rays from any suitable source of light onto the visible portion of an adjacent reflector, so as to cause said visible portion of a reflector carrying the design to emit light-rays into the eye of an observer.

The accompanying drawings, forming part of this application, illustrate the invention in its preferred form.

Figure 1 is a front view of the apparatus, exhibiting the numeral 3. Fig. 2 is a cross-section of the apparatus in the middle line of Fig. 1. Figs. 3 and 4 are detail views of parts of the reflectors.

1 in Figs. 1 and 2 is a casing or box surrounded by a frame-like structure 2. On opposite sides of this casing are bearing-strips 3, having openings to receive the bearing-studs 5 of the reflectors 4.

The reflectors illustrated in Figs. 3 and 4 consist of simple thin strips of any desirable material—such as sheet metal, cardboard, wood, &c.—and they rest on each side with their bearing-studs 5 in the openings of the stationary strip 3. Each reflector carries part

of the design to be exhibited, as indicated by the blank space on the surface of the reflectors in Figs 3 to 6 and in its totality by the design in Fig. 1. The reflectors may consist of relatively narrow thin strips, either straight, as in Fig. 4, or suitably curved, as in Fig. 3. It is obvious that the design may be produced in any desired color and that the same is not limited to the kind of a design such as shown in the drawings—namely, blank spaces on a relatively dark background.

The reflectors in some cases may be stationary, in which cases only that part of the same which is visible to the observer may be provided with a portion of a design, and the invisible part of the reflector may be painted white or any other suitable color or may be provided with a highly-polished surface, such as a mirror, in order to increase its reflecting power.

Should it be desired to exhibit more than one picture with only one apparatus, then each side of the reflectors may be provided with an appropriate portion of the designs; but means must be provided to turn the desired side of the reflector toward the observer. These means in a preferred form may consist of studs 6 on one end of an edge of each reflector, which studs 6 enter into suitable holes of a movable strip 7, so that by moving said strip 7 up and down either side of the reflectors may be made visible to an observer.

The design provided on the reflectors according to the hereinabove-given description will be very well visible in ordinary daylight; but in order to make the same visible at night or in dark places sources of light of any desired character, such as electric lights 8, must be provided for behind the reflectors. The rays of light originating from the source of light will first strike upon the back of each reflector, will be reflected therefrom unto the front of an adjacent reflector bearing part of a design and will then be thrown into the eye of an observer, producing therein a picture of great intensity and illumination and of surprising brilliancy.

Having now described the invention, that which is considered new and useful, and desired to be protected by Letters Patent, is—

1. In an illuminated device the combina-

tion with a series of substantially parallel reflectors, said series being ornamented on the front face thereof with a complete design and means located behind the series for illuminating said design.

2. In an illuminated device, the combination with a series of overlapping reflectors each reflector ornamented with part of one design, of a source or sources of light located behind the reflectors and adapted to throw light unto the ornamented side of the reflectors.

3. In an illuminated device, the combination with a series of substantially parallel reflectors ornamented with part of a design and means for illuminating the rear face of each reflector adapted to reflect light unto the front face of an adjoining reflector.

4. In an illuminated device, the combination with a box, of illuminating means therein and a series of substantially parallel reflectors each having part of a design and being inclined to the front face of the box.

5. In an illuminated device, the combination with a box, of illuminating means therein, a series of substantially parallel reflectors thereon each reflector having part of a

design and means for varying the angle formed by the planes of the reflector and the front plane of the box.

6. In an illuminated device, the combination with a casing of illuminating means therein a series of movable reflectors thereon each having part of a design, means for supporting said reflectors in said casing and operating means for said reflectors for varying the angle of inclination of the same to the front plane of the casing.

7. In an illuminated device, the combination with a casing of illuminating means therein, a series of reflectors thereon inclined to the front plane of the casing and having part of a design adapted to receive reflected light from the rear face of an adjoining reflector and means for movably supporting said reflectors in said casing.

In testimony whereof I have hereunto set my hand, in the presence of two subscribing witnesses, this 12th day of July, 1902.

MATHIAS L. JOLLY.

In presence of—

MARCUS C. HOPKINS,
E. EVERETT ELLIS.
